UNITED STATES PATENT OFFICE.

CHARLES M. LEECH, OF LIMA, OHIO.

GAS-ENGINE.

973,792.

Specification of Letters Patent. Patented Oct. 25, 1910.

Application filed May 1, 1909. Serial No. 493,296.

To all whom it may concern:

Be it known that I, CHARLES M. LEECH, citizen of the United States, residing at Lima, in the county of Allen and State of Ohio, have invented certain new and useful Improvements in Gas-Engines, of which the following is a specification.

My invention relates to gas engines of that class described and claimed in my Patent Number 914,292, embodying self-contained cylinder, and piston oiling and cooling means, the latter of which is comprised of a novel circulation of air and actuates the former.

15 My present invention aims to provide an improvement in the air circulation, whereby the cylinder and piston may be uniformly cooled, and the resulting warmed air employed to operate the oil and fuel feeds.

20 My invention further aims to provide a simplified structure, which will not therefore become often out of order, and which embodies a novel and useful throttle valve.

25 Further objects and advantages of my invention will appear in the course of the following description of the construction and operation thereof, in which reference is made to the accompanying drawings, forming a part of this specification, and in which,

30 Figure 1 is a central vertical sectional view through my improved engine, the form of which is similar to that shown in my patent above referred to. Fig. 2 is a partial side elevation and partial vertical section thereof, looking at right angles to Fig. 1. Fig. 3 is a central vertical sectional view of a shortened embodiment of my invention, in which the lower guide, shown in Fig. 1, is done away with, the operation however, remaining the same. Fig. 4 is a side elevation thereof. Fig. 5 is a similar view to Fig. 3, illustrating a slightly modified form. Fig. 6 is a plan view of the piston, removed. Fig. 7 is a side elevation of the throttle valve, 45 and, Fig. 8 is a cross section taken therethrough. Fig. 9 is a side elevation of the form of engine shown in Fig. 1. Fig. 10 is a detail view, partly in section, showing the cam and connecting rod.

50 Like numerals are used to designate like parts throughout the several figures, inasmuch as the forms are so nearly alike.

My improved engine comprises a casing 1, having an enlarged lower portion 2, forming the compression chamber, and a reduced upper portion 3, forming the explosion

chamber and having its exterior surface provided with radial vertical fins 4, for facilitating the circulation of air which is relied upon to cool chamber 3, and to increase 60 the exposed area. Said chamber 3 is formed centrally of its upper portion with a boss 5, having an internally threaded aperture 6, extending therethrough for the reception of a spark plug. Surrounding the chamber 3 65 is a jacket 7, which is spaced away from the edges of the fins 4, the lower circular edge of said jacket resting upon a circular shoulder 8 (Figs. 2 and 4) formed upon the outer surface of casing 1. The jacket 7 is formed 70 in its top with an opening 10, surrounding the boss 5 and affording an air admission port.

The crank case 12 is formed by a semi-circular casting 13, which has flanges 14, 75 extending upon a supporting base 15. The crank case, forms an oil chamber, and may be drained by means of a drain-pipe 16 leading from the lower central point of casting 13. According to the form shown 80 in Fig. 1, similar to the form shown in my patent, a casing 17, of semi-circular shape, is secured upon casting 13, and forms a part of the crank case, and supports the lower flanged edge 18 of casing 1, by its 85 circular flange 19 surrounding the central cylinder 20 thereof, while according to the form shown in Figs. 3 and 5, the lower edge of the casing 1, is secured directly upon the casting 13, thus doing away with casting 17, and reducing the length of the engine. 90

In Fig. 1, crank case castings 13 and 17, and in Figs. 3 and 5, casting 13 and the lower edge of casing 1, are provided in their 95 abutting faces, with recesses to form bearings 21 for the power shaft 22 having its crank 23 within the case 12.

The piston comprises a hollow cylindrical body 24, of a relative size to fit within the 100 explosion chamber 3, and has a circular flange 25, forming a piston and located within the compression chamber 2. Piston 24 and its flange 25 are also provided with suitable packing rings 26, and said piston 105 24 has a head 27, which receives the impact of the exploded charge within the explosion chamber 3, and is further provided with a transverse pin 28 to which the inner end of pitman 29 is coupled, the outer end of which pitman is coupled upon the crank 23 of shaft 22. 110

According to the form shown in Figs. 1 and 2, the piston 24 extends some distance beyond its flange 25, which extending portion 30 slides within the central cylinder 20 of crank case casting 17. In this form also casing 1 has diametrically opposing inlet and exhaust ports 31 and 32, respectively, leading through its wall into explosion chamber 3, which inlet opening 31 communicates with a vertical channel 33, through the casing wall, extending upwardly from a circular chamber 34 at the base thereof, below piston 25 to which a port 35 leads. The casing shoulder, between explosion and compression chambers 3 and 2 has openings 36 communicating between the compression chamber 2 above piston 25, and the jacket 7. A vertical pipe 37 located diametrically opposite to wall channel 33, has an upper angular end 38 leading through and communicating within jacket 7, and is also provided with connections 39 and 40, communicating respectively with the compression chamber 34 below piston 25 and the crank case 12, and provided respectively with valves 41 and 42. The chamber 34 below piston 25 has an outlet 43 diametrically opposite its connection 39 with pipe 37. Thus upon the up-stroke of piston 24, air is sucked downwardly through jacket 7, and pipe 37, and through valve 41 into chamber 34 below piston 25, and also into crank case 12 through 40 and 42 while upon the down-stroke thereof, such air is compressed and forced through channel 33 and outlet 43, and the air in crank case 12, previously drawn therein through valve 42, is compressed and expelled through parts to be hereinafter described. It will thus be seen that the explosion chamber and piston 24 will be thoroughly and uniformly cooled, the latter by the air drawn into the crank case 12, and that, after circulation, the resultant warmed air is collected within and expelled from chamber 34.

The form shown in Figs. 3 and 4, and the operation thereof, is very similar to that described, with the exception of the fact, as before stated, that the lower edge of casing 1 rests directly upon the crank case casting 13, and doing away with the piston extension 30, and the chamber 34 below piston 25. The air pipe 37, in this form, has its valved connections 39^a and 40^a communicating respectively with compression chamber 2 above piston 25, and with crank case 12 below said piston. Openings 36 through the casing shoulder, are thus dispensed with, air being taken in from jacket 7 through 39^a, and through 40^a to crank case from where it is discharged into channel 33 and outlet 43.

The form shown in Fig. 5, is also similar to the forms just described, especially Figs. 3 and 4, from which it differs only by the closing of the lower end of wall channel 33.

and providing a port 44 controlled by a valve 45, opening from compression chamber 2 above piston 25, into the wall channel 33.

In each of the forms of my invention shown, oil pipes 46 and 46^a are vertically and diametrically arranged upon opposite sides of said casting 1, the upper angular ends of each of said pipes 46 and 46^a being screw-threaded into the upper portion of said compression chamber 2, as at 47^a, near shoulder 8 and below exhaust pipe 38. The lower extended portion 46^b of the combustion chamber 3 is provided with openings 46^b in alignment with the open end 80 of said pipes 46 and 46^a. It is to be understood that pipe 46 communicates with the compression chamber 2 in exactly the same manner as pipe 46^a, and therefore I have illustrated only one of them. Upon the upper end of oil pipe 46 is mounted the oil can 47, which feeds oil into pipe 46 which oil is then distributed in any manner herein-after to be described.

The lower ends of pipes 46 and 46^a communicate with the central cylinder 20 of casting 17, near the lower end thereof. It is to be understood that the lower end of said pipes 46 and 46^a, except when piston 24 is in its lowermost position as shown in Fig. 1, are uncovered, and free to have communication with and deliver oil into crank case 12. Upon the upward stroke of piston 24, air is drawn into crank case 12, as before described, and upon the descent of said piston, a portion of the compressed air is forced upwardly through pipes 46 and 46^a. The oil dropping from oil can 47 into pipe 46 is sprayed through opening 46^b upon piston 24. It is obvious that a portion of the oil will gravitate downwardly through pipe 46, when the pressure is reduced therein by the upward stroke of the piston 24, and that said oil will be distributed upon the lower portion of the cylinder portion 20 of casting 17 for lubricating the same, and a portion of the same will be collected in crank case 12. The lower end of pitman 29 and crank 23 lubricate themselves by passing through the oil collected in crank case 12 and also splash the same upon the cylinder 20. The oil splashed into pipes 46 and 46^a, together with the air in crank case 12 which will be laden with small particles of oil, is forced upwardly through said pipes 46 and 46^a and in pipe 46^a is sprayed against cylinder 24 through opening 46^b, while in pipe 46 it is mixed with the oil dropping from can 47 and then sprayed against piston 24 as above described.

In accordance with my present invention, I provide a pipe 48 which leads from one of the air and oil pipes 46, shown in Figs. 2 and 4, and in the present showing, the pipe 46 to which oil cup 47 is connected, to the

exhaust pipe 49 leading from exhaust port 32, said air and oil pipe 46 being provided with a check or regulating valve 50 immediately above the connection thereto of pipe 48.

Check valves may also be provided at the bottom of air pipes 46 (see Fig. 2) to prevent air passing back into crank case. Thus for instance the air in chamber 2, Fig. 3 is, 10 on the up stroke, forced through pipes 46 and 48, and by means of the latter, into the exhaust pipe 49 to thoroughly clean out the latter of burnt gases which have just previously been thrown therein from the explosion chamber. Also in accordance with 15 my present invention, I provide a pipe 51 leading vertically from the outlet 43, and parallel alongside casing 1, to the upper end of which pipe 51 is secured a carbureter 20 comprising a casing 52, in which is mounted a central fuel receptacle 53, separated into upper and lower compartments by a centrally apertured web 54, the lower compartment of which has an inlet port 55, leading 25 through casing 52, which port is connected by means (not shown), to a suitable fuel tank containing fuel under pressure, and is controlled by a needle valve 56. The lower compartment of receptacle 53 contains a disk 30 valve 57 seated upwardly against the aperture in web 54, by a spring 58, said valve having a stem 59, the lower end of which is guided in said lower compartment and the upper end of which projects through the 35 aperture of web 54 and extends upwardly into the upper compartment within the path of downward movement of a valve 60, seated upwardly against the upper reduced end of receptacle 53, and having its stem 61, projecting upwardly through casing 52 and controlled by a spring 62, tending to hold 40 said valve against its seat. The upper compartment, as shown, communicates with the angular upper end 31 of the wall channel, 45 or, in other words, the inlet port of explosion chamber 3, by its outlet port 64 alined therewith. Thus a portion of the air which has been compressed in the compression chamber passes upwardly through channel 50 33 after being warmed by contact with piston 24, passes upwardly through pipe 51, and as soon as the piston descends, opening its exhaust and inlet ports, and reducing pressure in explosion chamber 3, said air 55 in pipe 51 will enter casing 52 and press valve 60 downwardly and enter the explosion chamber 3, through ports 64 and 31, carrying with it a portion of the fuel in the upper compartment of the fuel receptacle, 60 which is continuously supplied each time valve 60 is opened, by the contact of said valve against the upper end of the stem of valve 57, and the consequent lowering of the latter.

65 Extending vertically and upwardly from

the juncture of the explosion chamber inlet 31, carbureter outlet 64, and wall channel 33, and alined with the latter, is a scavenging pipe 65 which, at its upper end, has an angular extension 66, leading inwardly 70 through jacket 7 and casing 1, and communicating with the upper portion of explosion chamber 3, said pipe 65 having a back pressure check valve 67 therein, and permitting the entrance of air through from pipe 75 33 into the said chamber 3, as soon as exhaust port 32 is uncovered, to thoroughly force out all burnt gases. It will be understood that exhaust port 32 is uncovered prior to the uncovering of inlet port 31. Air pipe 80 48 assists in discharging the burnt gases by delivering air into exhaust pipes 49.

Arranged within the juncture of channel 33, pipe 65, and ports 31 and 64, is a throttle valve 68, having an outwardly extending 85 shaft 69 having a crank 70 upon its end to establish communication between said channels and ports at the proper times.

It is to be understood that valve 68 rotates backward and forward, just far enough 90 to cover and uncover pipes 65 and 64. Valve 68 keeps pipe 64 covered until the exhaust port 49 and inlet port 31 are opened, thus reducing the pressure in channel 33. If the valve 68 was not employed the air pressure 95 would enter pipe 64 and force open valve 57 and allow the gasoline or the like to escape, which might be very dangerous. Furthermore, it is desirous to have pipe 65 discharge air into the combustion chamber 100 3 after the air in channel 33 has been introduced therein, the construction of said valve being shown in detail in Figs. 7 and 8. This valve comprises a cylindrical body 71 having 105 a semi-circular section cut out therefrom between its ends, and provided with a central transverse conical opening 72, extending therethrough. A fine wire mesh 73 is secured to cover the cut-out portion just mentioned, and serves as a screen for the material projected through its opening 72. The valve 68 is shown in its open position in the drawing, from which it will be understood that, in its closed position, it covers the lower end of the scavenging pipe 65 and the discharge 110 end of the carburetor port 64.

The valve 68 is partially rotated so that the same may cover and uncover pipes 65 and 64, by means of a connecting rod 75 which has its upper end pivotally connected to a link 76, which in turn is pivotally connected to the crank 70. The rod 75 is slidably mounted in brackets 77, which are fixed upon the casing 1 and the rod 75 is rigidly connected as at 78 to the upper end of a coil spring 79, which is disposed between the brackets 77 and surrounds said connecting rod 75. The lower end of connecting rod 75 is provided with a fixed pin 80 upon which is rotatably mounted a wheel 81, adapted to 115 120 125 130

fit within a cam-groove 82, formed upon the outer side of a cam 83, which in turn is rigidly mounted the shaft 22.

Having fully described my invention, I claim:

1. In a gas engine of the character described, the combination of a cylinder feed channel, and a removable throttle valve therein comprising a solid cylindrical body 10 having a portion semi-circular in cross-section cut out therefrom between its ends, and with a conical opening extending transversely therethrough and communicating with the space made by the removal of said 15 cut-out portion, and a wire mesh secured upon said body to cover said space.
2. In a gas engine, a casing comprising explosion compression chambers, having different diameters, a crank case connected to 20 the lower end of said casing, a hollow piston disposed within said explosion chamber and provided with a flanged portion disposed within the compression chamber, said compression chamber opening downwardly into 25 said crank case, said explosion chamber having an inlet and outlet port, a jacket surrounding said explosion chamber, said compression chamber and said crank case forming air compressing chambers, air connections between said jacket and said air compressing chamber, said casing being provided with an opening in its wall communicating between one of said air compressing chambers and said explosion chamber inlet, 30 and a valved air connection between said opening and the upper portion of the explosion chamber, whereby to inject air into said explosion chamber each time the pressure is reduced therein by the uncovering of 35 the exhaust port.
3. In a gas engine, the combination with the feed channel of an explosion chamber, of a valve for controlling the same, comprising a body portion provided upon one side thereof with a cut out portion and upon its opposite side with an opening communicating with said cut out portion, and a section of wire gage arranged upon said valve for covering said cut out portion. 40
4. In a gas engine, a casing comprising an explosion chamber and a larger compression chamber, a hollow piston arranged within said explosion chamber and having a flanged portion disposed to operate within said compression chamber, a crank-case connected to 45
5. In a gas engine, a casing comprising an explosion chamber and a larger compression chamber, a hollow piston arranged within said explosion chamber and having a flanged portion disposed to operate within said compression chamber, means of communication between said jacket and said compression chamber, means of communication between said jacket and said crank-case, said explosion chamber being provided with inlet and exhaust ports, means of communication between said compression chamber and said inlet port, a device for holding fuel having means of communication with said inlet port, and means of communication between said compression chamber and the fuel holding device. 50
6. In a gas engine, a casing comprising an explosion chamber and a larger compression chamber, a hollow piston arranged within said explosion chamber and having a flanged portion disposed to operate within said compression chamber, a crank-case connected to 55
7. In a gas engine, a casing comprising an explosion chamber and a larger compression chamber, a hollow piston arranged within said explosion chamber and having a flanged portion disposed to operate within said compression chamber, a jacket surrounding said explosion chamber and provided with an air inlet, means of communication between said jacket and said compression chamber, means of communication between said jacket and said crank-case, said explosion chamber having inlet and exhaust ports, means of communication between said compression chamber and said inlet port, means of communication between said inlet port and the upper portion of said explosion chamber, a device for supplying material to said inlet port, and means of communication between said compression chamber and said device. 60
8. In a gas engine, an explosion chamber, a compression chamber, a closed crank-case, a piston disposed within said explosion chamber and having a flanged portion disposed within said compression chamber, said explosion chamber being provided with inlet and exhaust ports, an oil tank, means of communication between said oil tank and compression chamber and closed crank-case, and means of communication between said exhaust port and said last named means of communication. 65
9. In a gas engine, an explosion chamber, a compression chamber, a closed crank-case, a piston disposed within said explosion chamber and having a flanged portion disposed within said compression chamber, said explosion chamber being provided with inlet and exhaust ports, an oil tank, means of communication between said oil tank and compression chamber and closed crank-case, and means of communication between said exhaust port and said last named means of communication. 70
10. In a gas engine, an explosion chamber, a compression chamber, a closed crank-case, a piston disposed within said explosion chamber and having a flanged portion disposed within said compression chamber, said explosion chamber being provided with inlet and exhaust ports, an oil tank, means of communication between said oil tank and compression chamber and closed crank-case, and means of communication between said exhaust port and said last named means of communication. 75
11. In a gas engine, an explosion chamber, a compression chamber, a closed crank-case, a piston disposed within said explosion chamber and having a flanged portion disposed within said compression chamber, said explosion chamber being provided with inlet and exhaust ports, an oil tank, means of communication between said oil tank and compression chamber and closed crank-case, and means of communication between said exhaust port and said last named means of communication. 80
12. In a gas engine, an explosion chamber, a compression chamber, a closed crank-case, a piston disposed within said explosion chamber and having a flanged portion disposed within said compression chamber, said explosion chamber being provided with inlet and exhaust ports, an oil tank, means of communication between said oil tank and compression chamber and closed crank-case, and means of communication between said exhaust port and said last named means of communication. 85
13. In a gas engine, an explosion chamber, a compression chamber, a closed crank-case, a piston disposed within said explosion chamber and having a flanged portion disposed within said compression chamber, said explosion chamber being provided with inlet and exhaust ports, an oil tank, means of communication between said oil tank and compression chamber and closed crank-case, and means of communication between said exhaust port and said last named means of communication. 90
14. In a gas engine, an explosion chamber, a compression chamber, a closed crank-case, a piston disposed within said explosion chamber and having a flanged portion disposed within said compression chamber, said explosion chamber being provided with inlet and exhaust ports, an oil tank, means of communication between said oil tank and compression chamber and closed crank-case, and means of communication between said exhaust port and said last named means of communication. 95
15. In a gas engine, an explosion chamber, a compression chamber, a closed crank-case, a piston disposed within said explosion chamber and having a flanged portion disposed within said compression chamber, said explosion chamber being provided with inlet and exhaust ports, an oil tank, means of communication between said oil tank and compression chamber and closed crank-case, and means of communication between said exhaust port and said last named means of communication. 100

In testimony whereof I affix my signature in presence of two witnesses.

CHARLES M. LEECH.
